TOWEL CABINET

Application filed June 5, 1922, Serial No. 565,802. Renewed April 23, 1929.

The object of our invention is to provide a towel cabinet or holder in which a supply of reserve toweling can be kept ready for immediate use when the first roll is exhausted, thus relieving the janitor or laundryman of the necessity of making frequent trips to supply the cabinet with clean toweling.

A further object is to provide improved means for supporting the toweling in the cabinet, making it convenient to the delivery point and readily accessible for the laundry man.

A further and particular object is to provide a cabinet of such construction that the user can easily have access to the reserve toweling, but he must pull it out from the measuring device or feed roller, and the first toweling put into use must be carried across or over the feed roll and stop.

A further object is to provide improved means for regulating the feed of the clean toweling.

A further object is to provide improved means to prevent the withdrawal of the soiled toweling from the cabinet by any mischievous person or a user who is unfamiliar with the operation of the device.

Other objects of the invention will appear from the following detailed description.

The invention consists generally in various constructions and combinations, all as hereinafter described and particularly pointed out in the claims.

In the accompanying drawings forming part of this specification,

Figure 1 is a vertical sectional view through a towel cabinet embodying our invention.

Figure 2 is a detail sectional view showing the feed limiting device in its locking position,

Figure 3 is a similar view showing the device when tripped by the user to allow the delivery of the toweling,

Figure 4 is a sectional view on the line 4—4 of Figure 1.

In the drawing, 2 represents the base of the cabinet, having suitable supporting legs 3 and a chamber 4 for the soiled toweling, said chamber having a door 2^a for the removal of said toweling. The front of the cabinet near the top has an opening 5 through

which access may be had to the clean toweling and at the top of the cabinet is a cover 6 hinged to the rear wall at 7 and adapted to be raised to allow access to the clean toweling containing compartments and the feed roll. In the rear of the opening 5 and adjacent thereto is a curved partition 8 co-operating with the rear wall of the cabinet to form a toweling chamber 9. A shelf 10 is hinged at 11 to the rear wall of the cabinet and above this shelf is a second clean toweling chamber 9^a corresponding substantially to the one below the shelf. Within these chambers clean toweling-rolls 12 and 12^a are placed. A feed roll 13 journaled at its ends in the side walls of the cabinet is provided beneath the cover 6 and near the opening 5 and slightly above the roll 12^a and over this feed roll the web of clean toweling is stretched to depend within the cabinet in the rear of the opening 5 in position to be conveniently grasped by the user and drawn forward through the opening to a using position. The opening in the front of the cabinet is a suitable distance from the floor to allow the user to apply the web of clean toweling to the hands or the face, as desired.

Below the opening 5 in the upper part of the soiled toweling compartment is a plate 14 hinged at 15 to the front of the cabinet and having its inner end provided with a series of pins 16 which engage the web of toweling and should the user or any other person attempt to withdraw the soiled end of the toweling from the cabinet, this plate will be raised to the dotted line position shown in Figure 1 and contacting with the lower portion of the wall 8 will be checked in its upward movement and the pins engaging the web of toweling will positively prevent its withdrawal from the cabinet, while allowing sufficient slack to enable the person standing in front of the cabinet to use the clean section of the toweling conveniently. Stops 17 are mounted on the side walls of the cabinet to engage the plate 14 and limit its downward movement, supporting it at such an angle that the pins will surely engage with the soiled toweling web should there be any attempt to withdraw this web from the cabinet. In

this type of cabinet we prefer to provide a feed controlling device or stop which must be manipulated by the user before any clean towel can be obtained.

5 Many owners of buildings renting cabinets of this type prefer to have a stop device which must be released, or tripped by the user, as they have found it effects a considerable economy in the amount of toweling used. Many 10 persons, rather than take the trouble of operating the stop device to obtain an additional feed of the towel, will use a clean area of the towel that has been already drawn out by the previous operator and thus a roll of 15 towel will last much longer than when the feed is entirely automatic and only a pull on the towel is required to obtain a predetermined length.

At one end of the feed roll 6 we prefer 20 to provide a box or casing 18. A dog 19 is pivoted at 20 therein and is provided with prongs 21 and 22 projecting through a slot in the box to a point near the periphery of the roll 13 and said roll has a pin 23 in its 25 periphery in position to engage these prongs alternately and move the dog from one position to the other. For instance, as shown in Figure 2, the pin 23 is in contact with the prong 21 and thereby the roll is locked and 30 no feed of the towel can be obtained. Near the lower end of the dog is a slide 24 projecting outwardly through the wall of the cabinet and having a push button 25 thereon. A recess 26 is provided in the lower edge of 35 said slide to receive a pin 27 on the lower end of the dog 19. The inner end of the slide has a rounded surface 28 to contact with an incline 29 and a compression spring 30 normally tends to force the slide downwardly to 40 the position shown in Figure 2. When the user presses the button 25, the slide will be pushed in and the engagement of the end wall of the recess with the pin 27 will swing the dog 19 from the full line position in Figure 2 to the dotted line position in said figure, moving the prong 21 out of the path 45 of the pin 23 and allowing the feed roll to make one complete revolution. The oscillation of the dog 19 moves the prong 22 into 50 the path of the pin 23 so that when this pin is released and passes the prong 21, it will soon after engage the prong 22 and draw the dog back to the dotted line position in Figure 3, again setting the prong 21 in the 55 path of the pin 23. This will happen whether the user keeps his finger on the push-button or removes it. The feed roll can only make one complete revolution with each inward movement of the slide and if the user releases 60 the slide immediately after disengaging the prong 21 from the pin 23, the dog will be set in its locking position to prevent more than one revolution of the feed roll, regardless of whether the user keeps his finger on 65 the push-button or removes it. That is im-

material. The locking device is set with each revolution of the feed roll to prevent more than one revolution with each operation of the slide.

When the door 6 is raised or is open as 70 when the supply of clean towel is inserted, the attendant may easily and quickly stretch the towel over the delivery roll, and arrange to have the web hang down the desired distance without the necessity of dragging it over the delivery roll and repeatedly manipulating the lock device to allow the roll to be revolved. Furthermore, when the door is closed, a person standing in front of the cabinet would not be able, because of the proximity of the door to the feed roll, to raise the web out of engagement with the roll and draw out an unnecessary length of web from the cabinet. Hence the user will be obliged to manipulate the release of the lock device 80 and by so doing obtain a suitable length of towel for wiping purposes with each operation.

The cabinet as shown in Figure 1, has a closed back. The clean towel chamber is accessible only through the open top of the cabinet as heretofore explained and the soiled towel falling into the bottom of the cabinet may be reached through the door 2^a in the lower front panel. Hence the attendant in 90 caring for the cabinet does not find it necessary to move it out from the wall and have access to the back, as it can be readily filled with the clean towel and the soiled towel removed by the attendant standing in front of the cabinet. In using the cabinet the delivery feed roll will be released by the mechanism described, and then the user may pull out a certain predetermined length of clean 95 towel sufficient for wiping purposes. When the towel has been used and released, it will drop down in the soiled towel chamber and the engagement of the web with the pins in the gate 14 will positively prevent the soiled web from being pulled out of the cabinet. 100

105 We claim as our invention:

1. A towel cabinet comprising a casing having an opening in its upper walls for access to the clean towel, a feed roll above and adjacent said opening and over which the web of clean towel is delivered, and a plurality of towel compartments in the rear of and beneath said feed roll, one of said compartments being adapted to contain the roll of towel from which the web is conducted over 115 said feed roll, and the other compartment being adapted to contain a reserve towel roll to be placed in said first compartment when the roll therein is exhausted said second compartment being accessible only through the 120 first compartment whereby all of the first roll of toweling must be removed from said first compartment before the second roll can be used.

125 2. A towel cabinet comprising a casing hav- 130

- ing an opening in its upper walls for access to the clean towel, a feed roll above and adjacent said opening and over which the web of clean towel is delivered, and a plurality of 5 towel compartments in the rear of and beneath said feed roll, one of said compartments being adapted to contain the roll of towel from which the web is conducted over said feed roll, and the other compartment being adapted to contain a reserve towel roll to 10 be placed in said first compartment when the roll therein is exhausted said second compartment being accessible only through the first compartment whereby all of the first roll 15 of toweling must be removed from said first compartment before the second roll can be used, and a movable shelf interposed between said compartments and supporting the roll from which the towel web is being fed.
- 20 3. A towel cabinet comprising a casing having an opening in its upper walls for access to the clean towel, a feed roll above and adjacent said opening and over which the web of clean towel is delivered, and a plurality of 25 towel compartments in the rear of and beneath said feed roll, one of said compartments being adapted to contain the roll of towel from which the web is conducted over said feed roll, and the other compartment being adapted to contain a reserve towel roll to 30 be placed in said first compartment when the roll therein is exhausted said second compartment being accessible only through the first compartment whereby all of the first roll of 35 toweling must be removed from said first compartment before the second roll can be used, and a hinged shelf separating said compartments and adapted to be raised to an upright position to allow the convenient movement of the reserve roll from one compartment to the other.
- 40 4. A towel cabinet comprising a casing having a compartment in the lower portion for the soiled toweling and an opening in its upper front wall, a feed roll arranged above and near said opening and over which the clean towel web is delivered, a partition provided beneath said feed roll in the rear of said opening and co-operating with the rear 45 and side walls of said casing to form towel compartments, one above the other, the upper compartment being adapted to contain the roll from which the web is delivered over said feed roll, and the lower compartment being adapted to contain the reserve towel roll and accessible only through the first compartment, the top of said casing having a hinged section which, when raised, allows access to said towel compartments and said feed 50 roll.
- 55 5. A towel holder comprising a support for the clean towel, a feed roll over which the clean towel is fed, a dog for normally locking said feed roll against revolution, said dog having a pin thereon, a slide having a recess 60 to receive said pin and actuated by the finger of the user for moving said dog to its releasing position, said dog having means actuated by said roll for positively returning said dog to its locking position after the initial movement of said roll, means for guiding said slide upwardly out of engagement with the pin on said dog when inward pressure is applied to said slide, and a spring normally tending to return said slide to its engaging position with said dog when pressure of the user thereon is released.
- 65 6. A towel cabinet comprising a casing having an opening in its upper walls for access to the clean towel, a feed roll above and adjacent said opening and over which the web of clean towel is delivered, towel compartments in the rear of said feed roll opposite said opening, one of said compartments being adapted to contain the roll of towel from which the web is conducted over said feed roll, another compartment being adapted to contain a reserve towel, a guard extending upwardly from the reserve towel roll between it and said opening.
- 70 7. A towel holder comprising a support for the clean towel, a feeding means therefor having a stop, and a feed limiting device comprising a member having a pair of arms, one of them normally in the path of said stop to lock said feeding means, the other arm being positioned in the path of said stop when said member is moved to its release position for positively returning said member to its locking position before said feeding means completes its movement, a slide having a recess to loosely receive said member, whereby said member may become disengaged from said slide and positively returned to its locking position independently of the movement of said slide.
- 75 8. A towel cabinet having an open top and means therein to support a supply of clean towel, the upper front portion of the said cabinet having an opening therein merging into said top opening through which the user may reach the clean towel web, a feed roll in the upper front portion of said cabinet having a roughened surface over which the clean web may be stretched from the towel supply to depend in the rear of and adjacent said front opening, a cover for said top opening, the said cover having a downwardly extending front portion shielding said roll, whereby when the said cover is raised the clean towel web may be drawn up and stretched to 80 form a loop of the desired length at the front of the cabinet while out of contact with said roll to facilitate loading the cabinet.
- 85 9. A towel cabinet comprising a casing, a feed roll mounted in said casing adjacent the front of the cabinet and over which roll the web of clean towel may be stretched from a towel supply, said cabinet having a towel delivery opening, the web of clean towel being 90
- 95 100 105 110 115 120 125 130 135

adapted to normally depend from said feed roll where it may be conveniently reached by the user, said feed roll having a peripheral lug thereon, a lever pivoted intermediate to its ends below said feed roll and having a recessed part above its pivot conforming substantially to the curvature of said roll and provided with two spaced terminal prongs, one of which normally engages said lug to lock said roll, the second prong, by the initial release movement of said lever, being moved into the path of said lug, said lever being oscillated and said first named prong returned to its normal locking position by the engagement of said lug with said second prong upon the initial movement of said roll, and an operating device for said lever, the said device being freely connectible and disconnectible from said lever and having one end thereof projecting outwardly through a wall of said casing, whereby the towel user may first manipulate the lever to release said feed roll and then pull outwardly and downwardly on the towel web to revolve said roll and simultaneously return said lever to its locking position.

In witness whereof, we have hereunto set our hands this 27th day of May, 1922.

FRANK M. STEINER.
